UNITED STATES PATENT OFFICE.

WILLIAM C. COLEMAN, OF WICHITA, KANSAS.

DESIGN FOR A LAMP-SHADE.

53,266.

Specification for Design.

Patented May 6, 1919.

Application filed February 27, 1919. Serial No. 279,608. Term of patent 7 years.

To all whom it may concern:

Be it known that I, WILLIAM C. COLEMAN, a citizen of the United States, residing at Wichita, in the county of Sedgwick and State of Kansas, have invented a new, original, and ornamental Design for Lamp-Shades, of which the following is a specification, reference being had to the accompanying drawing, forming part thereof.

The figure is a view in elevation of the lamp shade, showing my new design.

I claim:

The ornamental design for a lamp shade, as shown.

W. C. COLEMAN.
